HELICOPTER

Marc A. Cardoso, Bronx, N.Y., assignor to
Samuel Chayes, Bronx, N.Y.

Filed Oct. 3, 1967, Ser. No. 8,844

Term of patent 14 years

Int. Cl. D12—07

U.S. Cl. D71—1

Fig. 2.

Fig. 3.

FIG. 1 is a front perspective view of a helicopter, showing my new design;

FIG. 2 is an elevational view showing one of the identical sides of the helicopter;

FIG. 3 is a rear perspective view;

FIG. 4 is a top plan view;

FIG. 5 is a front elevational view; and

FIG. 6 is a rear elevational view.

The characteristic features of my design reside in the portions shown by means of full lines in the drawing.

I claim:

The ornamental design for a helicopter, as shown and described.
